Primary Examiner — Elizabeth J Oswecki(74) *Attorney, Agent, or Firm* — Erise IP, P.A.(57) **CLAIM**

The ornamental design for a resistor as shown and described.

DESCRIPTION

FIG. 1 is an upper perspective view of a resistor;

FIG. 2 is a lower perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawings illustrate portions of the article that form no part of the claimed design.

1 Claim, 3 Drawing Sheets(56)
